UNITED STATES PATENT OFFICE

MORRIS TAX, OF MILWAUKEE, WISCONSIN.

Fixture Strap.

Application filed May 3, 1923. Serial No. 636,837.

To all whom it may concern:

Be it known that I, MORRIS TAX, a citizen of the United States, and resident of Milwaukee, in the county of Milwaukee and 5 State of Wisconsin, have invented certain new and useful Improvements in Fixture Straps; and I do hereby declare that the following is a full, clear, and exact description thereof.

10 This invention relates to a fixture strap.

In installing fixtures, particularly electric fixtures, it is the customary practice to provide a threaded hollow stud or nipple which projects outwardly from the wall of the 15 building. Upon this threaded stud a strap is secured and the ends of the strap are fastened to the ceiling collar or canopy. It is well known that the canopies vary widely in size and in the style. This necessitated the 20 carrying in stock of a large number of fixture straps to suit the varying needs.

Objects of this invention are to overcome the above noted defects and to provide a fixture strap which is adapted for use with 25 any type of ceiling collar or canopy so that one style of strap may be employed for the different sized canopies, and to provide an adjustable fixture strap which will securely support the canopy and which may be adjusted to accurately center the canopy with 30 reference to the threaded stud.

An embodiment of the invention is shown in the accompanying drawings, in which:—

35 Figure 1 is a face view of the fixture strap detached.

Figure 2 is a side view of the fixture strap showing in dotted lines the cooperating canopy supported thereby.

The fixture strap comprises a main plate 40 1 which forms a body for the strap, and which is provided with a centrally located threaded aperture 2 adapted to be screwed upon the threaded stud. This body plate carries four symmetrically located bolts 3 which may, if desired, be provided with slotted heads as shown in Figure 2.

A pair of end members 4 are positioned in 45 slidable relation upon opposite sides of the body plate 1. These end members are substantially U-shaped and are provided with parallel arms 6 and with slightly offset attaching portions 7 having rounded outer ends. The arms 6 are provided with elongated slots 8 adapted to receive the bolts 3, as may be seen from the drawings. The attaching portions 7 are provided with

threaded apertures 9 adapted to receive relatively short screws 10.

In using the device the exact adjustment desired may be most readily made by loosening the bolts 3 and adjusting the length of the device to fit within the upturned flange 11 of the ceiling collar or canopy, as shown in dotted lines in Figure 2—the rounded ends accommodating the usual curve found in the flanges of the canopy. Thereafter, the bolts 3 are tightened and the fixture strap is screwed into position upon the threaded stud. Thereafter, the canopy is positioned below the strap and the screws 10 passed 70 through holes regularly provided in the canopies and are screwed into the threaded holes 9 in the attaching portion 7 of the strap. It will thus be seen that the strap may be adjusted to the exact size desired, 75 and that the threaded aperture 2 may be accurately maintained in the correct relative position to the canopy.

It will also be seen that the spaced arms 6 of the end members provide the necessary 80 clearness so that the arms may pass the supporting stud upon which the strap is screwed thus providing a wide range of adjustment.

I claim:

1. A fixture strap comprising a body plate having a centrally located threaded aperture, a plurality of bolts carried by said body plate, and members having elongated slots through which said bolts pass, said members being slidably related to said body portion and having threaded apertures adjacent their outer portions.

2. A device for supporting an electric fixture from a stud, said device comprising a 85 body portion having an aperture therethrough for the reception of the stud, a pair of oppositely extending members slidably carried by said body portion and projecting laterally therefrom in substantially the 100 same horizontal plane, each of said members being substantially U-shaped and having its arms slidably carried by said body portion on opposite sides of the said aperture, said body portion having means for guiding said 105 arms and for maintaining them in superposed relation, the outer or yoke portion of said members having apertures for the reception of fixture attaching screws or bolts.

3. A ceiling band supporting element comprising a horizontal yoke substantially straight and flat from end to end thereof and

comprising a central section adapted to extend beneath and across a junction box and having an apertured central portion adapted to receive a fixture stem depending from 5 the junction box and a pair of fixed arms extending in the same horizontal plane in opposite directions from diametrically opposite sides of said apertured central portion, a pair of horizontally aligned separate 10 and independent extension arms slidably engaging the fixed arms and adjustable upon

the same in a horizontal plane parallel therewith, means for securing the extension arms in adjusted position upon the fixed arms, and means for attaching a ceiling band to the 15 outer ends of said extension arms beyond the outer ends of the fixed arms.

In testimony that I claim the foregoing I have hereunto set my hand at Milwaukee, in the county of Milwaukee and State of 20 Wisconsin.

MORRIS TAX.
